UNITED STATES PATENT OFFICE

HOWARD W. SWARTZ, OF GALESBURG, ILLINOIS

BATHROOM FIXTURE

Application filed November 17, 1928. Serial No. 320,191.

My invention relates to bath room fixtures and contemplates the provision of an accessory to the ordinary bath room appliances in the nature of a small apparatus employing a spray container for an antiseptic mouth wash and holder for the same, including means for operating the spraying device comprising an air compressor and flexible tube connection to the container for the mouth wash.

The primary object of my invention is to provide an apparatus of this character that can be readily and conveniently installed in the bath room of a private dwelling, hotel, 15 Pullman coach, and other structures in which a room for toilet purposes is provided whereby to furnish means for washing out the mouth for the proper care of the teeth in preventing pyorrhœa and other diseases of 20 the gums as well as mouth and teeth diseases.

A further object of my invention is to provide a bath room fixture or apparatus for spraying the mouth with an antiseptic liquid which can be readily installed in the wall 25 of a building already constructed, especially where the wall is in the form of a hollow partition so that the several parts can be located in the partition between the studding with the wall fixture supporting the removable mouth spraying device located above the washbowl into which it will be convenient to discharge the antiseptic liquid from the mouth in the use of the apparatus.

With these principal objects in view my 35 invention consists primarily in an inset wall fixture for bath rooms to receive and support a spraying container together with means for operating the spraying device including an air compressor and flexible tubing cooperating 40 with said wall fixture, all as hereinafter fully described and specifically set forth in the appended claims.

In the drawings:—

Figure 1 is a vertical sectional view showing 45 the apparatus installed in the wall of a bath room,

Fig. 2 is an enlarged detail sectional view of the fixture which supports the container and parts of the apparatus cooperating therewith, and

Fig. 3 is a front elevation of said fixture.

In carrying out my invention I employ a fixture 10 adapted to be inserted in an opening in the wall of a building in which the apparatus is to be installed, said wall fixture 55 being preferably in the form of a casting box-like in shape to present a recess or housing open at its front end with a rear wall 12, a bottom 13 inclined downwardly from said rear wall, and a surrounding frame 14 extended at its lower end to receive an element of the apparatus. The upper end of the box-like fixture may be also inclined as shown in the drawings and the surrounding frame or front portion thereof finished in any desired 60 ornamental design with screw holes 15 for securing the fixture in place. In order that the housing or recess formed by the fixture may receive and support the container or bottle having a spraying attachment the bottom wall 13 is provided with an opening 16 through which the body portion 17 of said bottle is passed for supporting the bottle from the enlarged spraying attachment 18 fixed to the upper end thereof and which rests 70 upon the bottom wall or a rubber gasket 19 fitted in the opening to serve as a cushion. Cooperating with the bottle receiving opening and located in proximity to the same there is an opening 20 in the rear wall through 75 which a flexible tube 21 extends from the valve 22 of the spraying device of the bottle and is connected to an air compressor 23, for forcing air through said spraying device, and for supporting the tube in the rear of the 80 fixture above the opening 20 a one-way coupling 24 is secured to the rear wall 12 and provided with nipples 24^a and 24^b to one of which said tube is attached, while to the other is attached a pipe 25 leading from the air 85 compressor. Furthermore, the downwardly extended frame or front portion of the fixture is provided with an electric switch 26, of a conventional type for controlling the circuit to the air compressor, the latter including 90 an electric motor (not shown) by which air is forced through the pipe 25 and tube 21 under a certain pressure, as for instance fifteen to twenty-five pounds.

It will be understood that the spraying de- 100

vice of the bottle containing the mouth wash is of the usual type in which the air is forced into the cap at one side thereof to draw the liquid from the bottle and discharge it in the form of a spray out of the nozzle 27, and as the air compressor is also of a conventional type I make no claim to either of these elements per se but to their association with other elements of the apparatus, consequently different types of spraying bottles and air compressors may be used without affecting the desired result.

When the apparatus is used as an accessory to a bathroom where the wall is in the form of a partition having studding 28 it is installed as shown in Fig. 1, the wall fixture 10 being set in an opening in the wall between the studding at a suitable elevation above the washbowl A and below the medicine cabinet B, and the air compressor located at a distance below said wall fixture to provide space for the flexible tubing which is connected to the spraying device, said air compressor being supported on cross pieces 29, and it will be noted that by this installation the only part of the apparatus showing in the bath room is the fixture 10 which provides the recess in the wall to receive the bottle containing the mouth wash and provide for feeding the flexible tubing to and from the housing space as well as a support for the coupling by which said tubing is connected to the pipe leading to the air compressor.

By the construction and arrangement hereinbefore described I provide a simple and compact apparatus that can be readily installed in a bath room or lavatory to provide means for the proper care of the mouth as well as through cleaning of the teeth, the bottle containing the antiseptic mouth wash being supported in a recess in the wall and connected to an electrically operated air pump or compressor by a flexible tube permitting the bottle to be withdrawn and the required manipulation of the same in directing the spray from the nozzle of the spraying device into the mouth of the user. In using the bottle containing the antiseptic mouth wash and having the spraying attachment the shape of the bottle affords a firm grip and the spraying attachment being longer than the body of the bottle provides a shoulder to prevent the bottle from slipping out of the hand, and of course the valve 22 may be manipulated by a finger of the hand holding the bottle so as to control the flow of air from the electric air pump or compressor controlled by the switch 26. After using the bottle it is returned to the wall fixture by inserting it in the recess 16 in the bottom of the recess formed thereby, the tube slipping through the opening 20 in the rear wall of said fixture so as to be housed in the space in the wall of the bath room between the wall fixture and air pump or compressor.

From the foregoing description in connection with the accompanying drawings it will be readily seen that I provide a bath room or lavatory with an accessory for using a spray in cleansing the mouth with an antiseptic, and in which the flow of air for the spraying device is furnished by an electrically operated air compressor controlled by the electric switch, it being understood that the air compressor is of that type by which the pressure will not exceed 25 pounds and consequently regulate the force of the spray so that it will not be harmful to the oral cavity.

Having described my invention, I claim:

1. In combination with a hollow wall, of an apparatus for use in connection with a bottle containing a mouth wash and having a spraying attachment, said apparatus comprising a wall fixture inset in the wall to form a recess therein, means for supporting the bottle in the recess, an opening through said fixture, and a pipe coupling on the rear wall of the fixture above said opening, together with an air compressor in the wall below the wall fixture to leave an intermediate space, a pipe connecting the air compressor to the pipe coupling, and a flexible tube extending from the spraying attachment of the bottle through the aforesaid opening and connected to said pipe coupling, the tube being housed in the space between the wall fixture and air compressor.

2. In combination with a hollow wall, of an apparatus for use in connection with a bottle containing a mouth wash and having a spraying attachment, said apparatus comprising a wall fixture inset in the wall to form a recess therein, means for supporting the bottle in the recess, an opening through said fixture, and a pipe coupling on the rear wall of the fixture above said opening, together with an electrically operated air compressor in the wall below the fixture to leave an intermediate space, a pipe connecting the air compressor to the pipe coupling, a flexible tube extending from the spraying attachment of the bottle through the aforesaid opening and connected to said pipe coupling, the tube being housed in the space between the wall fixture and air compressor, and an electric switch carried by the wall fixture to control the operation of the electric air compressor.

3. A bath room wall fixture for use in connection with a bottle having a spraying attachment connected by flexible tube with an air compressor, comprising a box-like casting forming a recess with an opening through the bottom of the fixture to receive and support the bottle, and an opening through the fixture adjoining the bottle through which the flexible tube is extended from the spraying attachment on said bottle, a pipe coupling on the rear wall of the fixture for connection of the flexible tube and air compressor to said fixture, and an electric switch on the front

of the fixture to control the operation of the air compressor.

4. A bath room wall fixture to receive and support a bottle having a spraying attachment, comprising a box-like structure forming a recess open at its front end with a frame surrounding said recess, the bottom of the recess being inclined forwardly and downwardly and provided with an opening therethrough, an opening in the rear wall of the fixture adjacent the aforesaid opening, and an electric switch attached to the frame of the fixture.

5. A bath room wall fixture to receive and support a bottle having a spraying attachment, comprising a box-like structure forming a recess open at its front end with a frame surrounding said recess, the bottom of the recess being inclined forwardly and downwardly and provided with an opening therethrough, an opening in the rear wall of the fixture adjacent the aforesaid opening, an electric switch attached to the frame at the front of said fixture, and a pipe coupling attached to the rear wall of the fixture.
